(No Model.)

J. WAE SPI, E. FRETZ, J. SPELLMAN & J. FREY.
FILTER.

No. 373,257.

Patented Nov. 15, 1887.

UNITED STATES PATENT OFFICE.

JACOB WAESPI, EMIL FRETZ, JOHN SPELLMAN, AND JOHN FREY, OF DALLAS, TEXAS.

FILTER.

SPECIFICATION forming part of Letters Patent No. 373,257, dated November 15, 1887.

Application filed March 31, 1887. Serial No. 233,163. (No model.)

To all whom it may concern:

Be it known that we, JACOB WAESPI, EMIL FRETZ, JOHN SPELLMAN, and JOHN FREY, all of Dallas, in the county of Dallas and State of Texas, have invented a new and Improved Filter, of which the following is a full, clear, and exact description.

The object of our invention is to provide a new and improved filter for purifying water intended for the use of cities, towns, &c.

The invention consists of various parts and details and combinations of the same, as will be fully described hereinafter, and then pointed out in the claim.

Reference is to be had to the accompanying drawings, forming a part of this specification, in which similar letters of reference indicate corresponding parts in all the figures.

Figure 1 is a plan view of our improvement, showing a double filter. Fig. 2 is a longitudinal sectional elevation of the same on the line *xx* of Fig. 1. Fig. 3 is a vertical cross-section of the basin on the line *yy* of Fig. 1. Fig. 4 is a vertical cross-section of the gravel-chamber on the line *zz* of Fig. 1, and Fig. 5 is a vertical cross-section of the receiving-chamber on the line *uu* of Fig. 1.

In the construction of our improved filter we may employ only one filter; but we prefer to arrange two or more filters alongside of each other, each working independently of the others, but being alike in construction.

In the drawings we show two filters, A A, which are placed alongside each other and separated by a longitudinal partition-wall, B. The filters are built of suitable material and placed on a good foundation of masonry. Each filter A consists of a receptacle, C, placed in an inclined position, and of an exit-basin, D, located horizontally at the foot of the receptacle C. The receptacle C is provided on its upper end with a receiving-chamber, E, in the bottom of which is held a perforated pipe, F, provided with a valve, F', and connected by the branch pipe F² with the main water-supply pipe G, having a valve, G', for regulating the flow of water into the branch pipes F². A drain-pipe, E', leads to the outside from the lower end of the receiving-chamber E through one of the side walls of the same. This pipe E' is provided at its outer end with a valve.

The lower wall, E², of the receiving chamber E is somewhat less in height than the chamber-walls, so that the water flows over the lower wall, E², into the settling-chamber H, 55 provided on its lower end with a drain-pipe, H', and with a lower end wall, H², over which the water flows into the gravel-chamber I, which is filled with clean gravel entirely free from sand. In this chamber I are arranged, 60 at suitable intervals, the transverse wedge-shaped ridges I', on which the impurities of the water accumulate, which impurities are drawn off, whenever desired, by the drain-pipe I', connected with each ridge and leading to 65 the outside.

The lower end wall of the gravel-chamber I consists of a perforated plate, I², through which the water passes into the exit-basin D, which may be provided in its center with a transverse box, J, having perforated sides and containing charcoal, through which the water passes before reaching the outlet-pipe K, which connects the said basin D with the water-mains or suction-pipes of pumping-engines. 70

In the basin D are arranged several drain-pipes, D', for drawing off impurities when cleaning the basin. The object of the receiving and settling chambers E and H is to break the flow and the rush of the water, so that it 75 passes quietly into the gravel-chamber I, in which it passes through the gravel, which drives it of its impurities, which settle on the bottom, principally against the ridges I'. The impurities settling alongside the ridges I' can 80 be drawn off whenever desired through the drain-pipes I². The perforated plate I² permits the passage through it of the water into the basin D, in which the water, should it possess a disagreeable odor, is deprived of the 85 same in passing through the charcoal-box J, and it finally enters the main outlet-pipe K in a pure and healthy state.

The several chambers of each filter can easily be cleaned by closing the valve F', thus shutting off the supply of water, and then the several drain-pipes E', H', I', and D' are opened, so that the water in these several chambers is drawn off. The chambers E H and the basin D are cleaned by the use of a hose, L, connected with 90 a plug, N, on the branch pipe F².

In order to clean the gravel-chamber I, it is

necessary that part of the gravel in the upper part of the chamber should be removed, and the remaining part is washed by the hose L, as illustrated in Fig. 1. The impurities on the bottom settle against the first ridge and pass out through the first drain-pipe, I', connected with the said ridge. The gravel is then replaced, and the following sections of the chamber I are washed in the same manner, if necessary. The arrangement shown in the drawing permits of cleaning one of the filters while the other is working.

Having thus fully described our invention, we claim as new and desire to secure by Letters Patent—

The filter consisting of the receptacle having the receiving, settling, and filtering chambers, in the bottom of which filtering chamber are formed transverse wedge-shaped ridges,

and at the bottoms of the receiving, settling, and filtering chambers and of the basin are arranged outlet-pipes, which receiving, settling, and filtering chambers are separated from one another by walls or partitions of successively varying or lesser heights, and which basin is arranged lower than the filtering chamber, together with a branched supply-pipe connecting with valved perforated pipes arranged in the receiving-chamber, substantially as and for the purpose specified.

JACOB WAESPI.
EMIL FRETZ.
JOHN SPELLMAN.
JOHN FREY.
